(73) Assignee: **Philips Electronics North America
Corporation**, New York, NY (US)

Primary Examiner—Nanda Bondade

(**) Term: **14 Years**

(57) **CLAIM**

(21) Appl. No.: **29/131,710**

The ornamental design for user-interface for a multi-channel digital video recorder, as shown and described.

(22) Filed: **Oct. 26, 2000**

DESCRIPTION

(51) LOC (7) Cl. **14-01**

FIG. 1 is a perspective view showing my design;

(52) U.S. Cl. **D14/135; D14/217**

FIG. 2 is a front elevational view thereof;

(58) Field of Search D14/135, 136,
D14/156, 188, 217, 257, 258, 265, 299;
455/6.1, 6.2

FIG. 3 is a right side elevational view thereof;

FIG. 4 is a left side elevational view thereof;

FIG. 5 is a top plan view thereof; and,

FIG. 6 is a bottom plan view thereof.

The broken line showing on FIGS. 1-6 is for illustrative

purposes only and forms no part of the claimed design.
